UNITED STATES PATENT OFFICE.

ISIDOR KITSEE, OF PHILADELPHIA, PENNSYLVANIA.

TELEGRAPHIC RECEIVING DEVICE.

No. 846,416.

Specification of Letters Patent.

Patented March 5, 1907.

Application filed September 6, 1906. Serial No. 333,497.

To all whom it may concern:

Be it known that I, ISIDOR KITSEE, a citizen of the United States, residing at Philadelphia, in the county of Philadelphia and State of Pennsylvania, have invented certain new and useful Improvements in Telegraphic Receiving Devices, of which the following is a specification.

My invention relates to an improvement in telegraphic receiving devices or relays. Its object is to translate the incoming impulses on lines with great capacity, such as submarine cables, into sound or relay the same to a second line.

For the purpose that persons versed in the art may practice this my invention I have illustrated the same as being applied to the well-known siphon-recorder, a device usually employed in submarine-cable work, and I have replaced the siphon proper by two light conductors, such as conducting-wires of small dimension. Where the conducting liquid, which will hereinafter be described, is a fluid not affecting aluminium, the wire may consist of this metal; but where diluted sulfuric acid or the like is employed it is best to use a platinum wire. The same does not need to be more than one-hundredth of an inch in diameter.

In the drawing, Figure 1 is a perspective view of this recorder with my invention attached thereto. Fig. 2 is a section of one of the conducting liquids employed by me.

1 is the electromagnetic part of the siphon-recorder provided, as usual, with the supporting-piece 2; but instead of having attached to this piece the siphon proper there are attached to it the two conductors 3 and 4.

7 is a retaining vessel, of non-conducting material and divided into two parts, one part containing the fluid 8 and one part containing the fluid 9. This fluid has to be conducting, and it is preferred that diluted sulfuric acid should be used.

The conductor 3 terminates at the lower end in the bent portion 5, and the conductor 4 terminates in the lower end in the bent portion 6.

10 is a retaining vessel, preferably of conducting material. This vessel contains the conducting fluid 12 and the non-conducting fluid 11. The conducting fluid may also in this case consist of diluted sulfuric acid, and the non-conducting fluid may consist of one

of the lighter oils—such, for instance, as petroleum.

The containing vessel 7 is provided with the contacts 19 and 20, the contact 19 connected through wire 18 with the source of current 17 and the contact 20 connected through wire 21 with the source of current 16. Both sources are connected together with the positive pole through wire 26, and this wire is connected through wire 15 with contact 14 of the containing vessel 10. Normally the conductors 3 and 4 connect with one end with the conducting liquids 8 and 9, respectively. The other end of both wires just touch the conducting liquid 12. It is therefore seen that a short circuit of the two batteries 16 and 17 is established.

30 is an electromagnet, such as a sounder; but instead of providing the sounder with the usual spring I have provided the same with two sets of electromagnets—one near one terminal of the lever 29 and the second near the other terminal of said lever. The sets of electromagnets are designated by the numerals 23 and 27, respectively, and they are joined by the wire 24. The circuit of the electromagnet 27 is made through wire 28 and return 25. The circuit of the electromagnet 23 is made through wire 22 and return 25.

As long as a conducting-path between the upper and lower reservoir is established the electromagnets 23 and 27 will not be operated upon, for the reason that the circuits are arranged so that the part including the conductors 3 and 4 is of far lower resistance than the path embracing electromagnet 23 or 27; but as soon as the electric continuity between the upper and lower reservoirs is broken then the electromagnet connected to the respective source of current will be actuated.

It is supposed that the end of the lever near the screw 31 is normally in an upward position, and therefore the opposite end in a downward position. It is also supposed that the wire closing the shunt of battery 17 will be actuated so as to come out of the conducting liquid 12 by a positive impulse and the wire connecting the shunt of battery 17 through an impulse of opposite polarity, and it is supposed that the positive impulse is the signaling impulse and the impulse of opposite polarity the spacing impulse.

The operation of this device is as follows:

Normally, as said above, both the wires 3 and 4 dip with their lower end in the conducting liquid 12. Both batteries therefore are short-circuited. The transmitting operator 5 impresses now upon the line a positive impulse. This impulse will move the coil of the siphon-recorder in a manner so that the lower part 6 of the conductor 4 will be moved out of the conducting liquid and in the region 10 of the non-conducting liquid or oil. Through this movement the shunt around the battery 17 will be broken, and the circuit of this battery, including the electromagnet 27, will be 15 become operative. The end of the lever 29 near the screw 31 will be pulled downward and will produce what is known in telegraphy as the "downstroke." When after a shorter or longer period the transmitting operator impresses upon the line a negative impulse, 20 the coil of the recorder will be moved in a direction so as to replace again the lower end 6 into the conducting liquid, but move out of the conducting liquid and into the region of the non-conducting fluid the lower end 5 of 25 the wire 3. Through this movement the shunt around battery 16 will be broken, and the circuit of this battery, including the electromagnet 23, will be made operative and the lever end near the electromagnet 23 will be 30 pulled downward, and therefore the end in proximity to screw 31 pulled upward, and this will produce what is technically known as the "upper stroke." In telegraphing today over land-lines the translating device, 35 such as a sounder, operates in about the same manner, the downstroke designating the signal, the upper stroke designating that the spacing commenced, and the time unit lapsing between the downstroke and the 40 upper stroke designating the character transmitted, if the same is a dot or dash. In land telegraphy the operator closes the key for a short period—say one time unit to denote a dot, and for a longer period say three 45 time units to denote a dash. In this system the operator impresses upon the line a positive impulse producing the downstroke, and if he desires to transmit a dot he impresses upon the line in one unit of time a negative 50 impulse, thereby producing the upper stroke, and if he desires to transmit a dash he allows three time units to lapse before impressing upon the line a negative impulse. In such method of telegraphy the operator always 55 closes his message with the negative impulse, and the normal position of the device 30 will therefore be always such that the lever end near the screw 31 will be in an upward position. Such in broad outlines is the aim of 60 my invention; but it is obvious that the details of same may be varied without departing from the scope of my invention. If it is desired to relay the cable, the localized device can be provided with means to produce 65 such results, and I have here only illustrated

the terminals of two circuits which may be operated through the device 30.

I am aware that instead of short-circuiting the batteries 16 and 17 with the aid of the conductors 3 and 4 the electromagnets 23 and 27 may be placed in this circuit, so that through the opening or closing of this circuit these electromagnets may directly be operated; but I have found that the arrangement as illustrated and described is to be 75 preferred, because the movements of the wires are very small and their suspension very delicate. The breaking of the circuit will therefore often produce sparking, which is detrimental for the successful working of 80 the device.

Having now described my invention, what I claim as new, and desire to secure by Letters Patent, is—

1. In a device of the class described, means 85 to operate a local circuit, said means comprising two conductors connected each electrically with a separate conducting liquid and connected both jointly with a second conducting liquid; a local circuit for each of 90 said conductors and means operatively related to the device, inserted in the line, to move one or the other of the conductors in and out of the region of the second conducting liquid.

2. In combination with a telegraphic receiving device, means to operate therewith a local circuit embracing translating device, 95 said means comprising two conductors, operatively related to the receiving device, a conducting fluid for one terminal of each of said conductors and a second conducting fluid common to the second terminal of both of 100 said conductors, a non-conducting fluid for the second conducting fluid, a circuit for each 105 of said conductors and a translating device for said circuits.

3. In telegraphy, a receiving device inserted in the line of transmission, two conductors for same, a separate fluid contact for one terminal of each of said conductors, a fluid contact common for the other terminal of both conductors, a local circuit for each of 110 said conductors, said local circuit adapted to be operated through the movement of one 115 or the other of said conductors.

4. In telegraphy, a receiving device, two conductors in operative relation to the movable part of said receiving device, two local circuits, each of said conductors in operative 120 relation to one of said circuits through fluid conductors, a translating device common to both of said circuits, each of said circuits adapted to be operated through one of said conductors.

5. In combination with a receiving device comprising stationary magnets and a movable coil, two conductors mechanically related to said coil, a local circuit for each of 125 said conductors, a translating device com- 130

mon to both of said local circuits and means to operate one or the other of said local circuits through the movement of one or the other of said conductors.

5 6. In combination with a receiving device, two conductors related to the movable part of said receiving device, liquid contacts for each of said conductors, a local circuit for each of said conductors, a translating device common to both of said local circuits, said

translating device adapted to be operated through the movement of one or the other of said conductors.

In testimony whereof I affix my signature in presence of two witnesses.

ISIDOR KITSEE.
